CLAIM

The ornamental design for a stationary holder with cat motif, as shown and described.

DESCRIPTION

FIG. 1 is an isometric perspective view of embodiment 1 of a stationary holder with cat motif;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and

FIG. 7 is a bottom plan view thereof.

FIG. 8 is an isometric perspective view of embodiment 2;

FIG. 9 is a front elevation view of embodiment 2;

FIG. 10 is a rear elevation view of embodiment 2;

FIG. 11 is left side elevation of embodiment 2;

FIG. 12 is right side elevation of embodiment 2;

FIG. 13 is a top plan view of embodiment 2; and,

FIG. 14 is a bottom plan view of embodiment 2.

The broken lines shown in the drawings represent portions of the stationary holder with cat motif that form no part of the claimed design.
